UNITED STATES PATENT OFFICE.

WILLIAM TUNSTILL, OF PATERSON, NEW JERSEY.

IMPROVEMENT IN BRAIDING-MACHINES.

Specification forming part of Letters Patent No. 36,249, dated August 19, 1862.

To all whom it may concern.

Be it known that I, WILLIAM TUNSTILL, of Paterson, in the county of Passaic and State of New Jersey, have invented, made, and applied to use a certain new and useful Improvement in Braiding-Machines; and I do hereby declare the following to be a full, clear, and exact description of my said invention, reference being had to the annexed drawings, making part of this specification; wherein—

Figure 1 is a front elevation of my machine. Fig. 2 is a side elevation. Fig. 3 is a plan of the stop-motion lever. Fig. 4 is an elevation of one of the spools, with the stop-motion weight applied thereto; and Fig. 5 is a plan of the take-up rollers.

Similar marks of reference denote the same parts.

In machines for braiding much inconvenience is experienced from the loss of room consequent upon the length of cross belt required from the horizontal shaft to the main vertical shaft of the machine. This is particularly the case with machines for braiding the covering of wire or springs for hoop-skirts, because a number of said machines set in a row and driven by a horizontal shaft occupy much more room than is actually required for the machinery itself, because the length of belt essential in practice causes the machine to be at some little distance from said main shaft.

The nature of my said invention consists in the arrangement of a stop-motion lever and miter-gears, located between the main vertical shaft of the machine and the main driving-shaft, in such a manner that the machine is rendered much more compact than heretofore, and greater regularity in the movements is insured.

In the drawings, *a* is the frame of the machine, adapted to receive a braiding-machine on each side, as seen in Fig. 2.

b is the main horizontal driving-shaft.

c is a pulley thereon, with a belt, *1*, to the pulley on the miter-gear *d*, that revolves on a horizontal stud from the frame *a*.

e is the vertical shaft, from which motion is given to the parts of the braiding-machine. *f* is a miter-wheel on this shaft *e*, set to slide vertically on a feather or seat in said shaft.

g is a lever with an eye passing said shaft *e* and acting below the wheel *f* to hold it up

into gear with *d*; but when this lever drops the miter-gear also falls and disconnects from the wheel *d*, and the machine stops. By this arrangement greater regularity in the rotation of the machine is insured, as the belt *1* is not as liable to slip as the partially-crossed belt heretofore employed.

h is a catch-bar taking over the horizontal stop-motion lever *k*, which catch, when over said lever *k*, holds up the lever *g*; but when said stop-lever *k* is moved aside by the weight that falls when a thread breaks the catch-bar *h* drops and stops the machine. *x* is a spring to keep this lever *k* toward the latch *h*.

i is the grooved or slotted plate through which the spool-carriers travel, as now usual in any braiding-machine, and *l l* are the gear-wheels, and *m m* the notched disks that carry said spools through the slots of said plate *i*; and as this portion of the well-known braiding-machine is only here introduced to illustrate the application of my improvement, this device does not require further description.

The spools *3*, weights *4*, and stop *5* to the spool are all of the usual character, and the thread holds up the weight *4*; but said weight falls if the thread breaks, and by the projections at the bottom of the weight acts upon the stop-lever *k*.

My improvement in the stop-lever *k* consists in providing the cam shaped end *6*, located nearly equidistant from either groove *7* or *8* in the plate *i*, as seen in Fig. 3, so that the machine will be stopped in consequence of one of said weights *4* taking this lever, whether the spool and weight are moving in one direction in the slot or groove *7* or in the other direction in the slot or groove *8*. The wire or material to be covered with the braided threads from the spools *3* is sustained in a spool, *9*, below the plate *i*, and is to pass through a hole in said plate; but if the braiding is not to be over a core or wire this spool *9* is not needed. The braided material is drawn through with uniformity by means of the rollers *o* and *p*. The roller *o* is formed with grooves more or less in diameter, so that the amount of material drawn through with a given speed of the shaft *o*, by which said roller is turned, may be increased or decreased. This shaft *o* is revolved by a wheel, *10*, and worm *11* on the vertical shaft *e*.

The roller *p* is loose on its axis to turn freely, and is kept to the material, between that and the roller *o*, by a bar, 12, and screw 12', that act upon the axis 14 of said roller *p*, and a block of india-rubber at 15 allows this roller *p* to yield to any inequality of the material.

q is the roller or spool on which the braided material is to be wound. This is on the short shaft 16 and driven by the belt 17 from the cone of pulleys 18 on the shaft *o*'. This belt 17 has to act with a certain amount of friction to wind up the braided material. If too much friction is applied in consequence of the belt being too tight, the material will be unduly strained, particularly when the spool is almost full. This friction has heretofore been regulated by lacing up the belt to the required length. This is both troublesome and difficult on account of the shortness of the belt. I therefore mount the shaft 16 in vertical slots in the standards 19 and apply set-screws 20 20 below, whereby the tension and friction of the belt are adjusted with accuracy.

To lay the braided material upon the spools

q uniformly and evenly, I employ the traverse-bar *r*, with a loop, 21, to pass the braided material, and this bar is actuated by the heart-shaped cam *s*, lever *t*, and rod *t*'. This cam *s* is rotated by a wheel, *w*, and worm on the shaft *v*, driven by the wheel *w* and worm on the main shaft *b*.

In place of the belt 1, from the driving-shaft *b* to the pulley on the miter-gear *d*, a spur-wheel might be made use of to gear into a similar wheel placed on the main driving-shaft.

What I claim, and desire to secure by Letters Patent, is—

The arrangement of the lever *g*, catch-bar *h*, and stop-motion lever *k*, in combination with the miter-gears *d* and *f*, as and for the purposes set forth.

In witness whereof I have hereunto set my signature this 5th day of June, 1862.

WILLIAM TUNSTILL.
